UNITED STATES PATENT OFFICE.

LUCIUS H. DANCY, OF HOLLY SPRINGS, MISSISSIPPI.

FOUNTAIN-COMB.

1,058,560.

Specification of Letters Patent.

Patented Apr. 8, 1913.

Application filed December 7, 1912. Serial No. 735,392.

To all whom it may concern:

Be it known that I, LUCIUS H. DANCY, a citizen of the United States, and a resident of Holly Springs, in the county of Marshall and State of Mississippi, have invented a new and Improved Fountain-Comb, of which the following is a full, clear, and exact description.

My invention relates to improvements in 10 toilet articles used for applying liquids to the scalp when dyeing the hair or when removing dandruff from the scalp while combing the hair.

The invention has reference more particularly to an article comprising a comb and a container for a liquid removably associated with the comb.

An object of the invention is to provide an inexpensive and simple fountain comb 20 for dyeing the hair or removing dandruff from the same, in which the container is removable from the comb and can be easily cleaned and in which the flow of liquid is controlled by pressure applied to the container, the liquid being distributed evenly to the surface of the teeth of the comb.

Another object of the invention is to provide a fountain comb having a flexible and resilient container disposed over the comb 30 and in which pressure applied by the fingers of the hand is distributed uniformly over the surface of the container.

Reference is to be had to the accompanying drawings forming a part of this specification in which like characters of reference indicate corresponding parts in all the views, and in which—

Figure 1 is a perspective view of an embodiment of my invention; Fig. 2 is a vertical section of the same, showing it in normal position; Fig. 3 is a similar section showing the same in application; and Fig. 4 is a perspective view of the comb with the container removed.

Referring to the drawings, 10 represents a flexible receptacle made of resilient material, preferably cylindrical in form, having a longitudinal reinforcement 11 and an opening provided with a plug 10' through which the liquid is introduced into the container or receptacle. The reinforcing portion 11 is interiorly provided with a longitudinal recess 12 having a V-shape in cross section and forming part of the container.

A series of transverse orifices 13 is provided 55 in the reinforcing portion 11, passing through said V-shaped recess and therefore forming discharge orifices on both sides of the reinforcing portion 11 of the container 10. Engaging the orifices 13 and projecting through the same are teeth 14 of a comb 15, the body 16 of which is preferably turned up, as shown in the drawings, and made to contact with the lateral surface of the container, as shown best in Fig. 2. In 60 consequence of the resiliency of the material from which the container is made, the teeth of the comb engaging in the discharge orifices close the same and prevent the liquid in said container from overflowing when in 65 normal position; see Fig. 2.

When the article is in use, as shown in Fig. 3, the portion of the container toward the extremities of the teeth of the comb is forced away from the teeth and thereby the 75 discharge orifices on this side of the comb are expanded by the pull allowing the escapement of liquid which will naturally flow along the teeth of the comb. The opposite side of the container being forced toward the raised portion 16 of the comb is 80 compressed, and consequently the orifices on this side of the reinforcement 11 will prevent any outflow of liquid through the same.

To make the outflow of liquid uniform at all parts of the container, the same is provided on its exterior lateral surface with a rigid member 17 attached to the material of the container in any suitable way. Said 85 member is preferably located at an angle of approximately 90 degrees from the reinforcing portion 11, and is always disposed toward the extremities of the teeth of the comb. When using the article, finger pressure is applied to the member 17.

It can be easily seen that any shaped comb can be used in connection with the container as long as the discharge orifices are made to fit tight with the teeth of the comb, 100 and the amount of outflow through the discharge orifices can be easily controlled by pulling on the container to make the discharge orifices expand according to the desired discharge. The comb can be easily 105 withdrawn from the discharge orifices of the container to be cleaned or used for ordinary purposes, if desired.

Having thus described my invention, I claim as new and desire to secure by Letters Patent:—

1. In an article of the class described, a flexible container having a series of discharge orifices, and a comb having its teeth associated with said orifices and projecting through the same, for the purposes set forth.
2. In an article of the class described, a container of resilient material having an exteriorly longitudinal reinforcing portion and discharge orifices in said reinforcing portion, and a comb having its teeth engaging said discharge orifices and projecting through the same, for the purposes set forth.
3. In an article of the class described, a flexible container having a rigid member on its lateral surface and a series of discharge orifices, and a comb having its teeth

engaging said orifices and projecting there-through, said comb forming a support for said container.

4. In a device of the character described, the combination of a liquid container having a flexible portion provided with a discharge orifice, and a comb associated with said container and having a tooth projecting through said orifice, whereby when the flexible portion of the container is distorted, the liquid will be discharged above said tooth.

In testimony whereof I have signed my name to this specification in the presence of two subscribing witnesses.

LUCIUS H. DANCY.
